UNITED STATES PATENT OFFICE.

FREDERICK G. JORDAN, OF CEMENT, WASHINGTON.

REINFORCING ELEMENT FOR CEMENT AND CONCRETE WORK.

1,294,278.

Specification of Letters Patent. Patented Feb. 11, 1919.

Application filed May 11, 1916. Serial No. 234,008.

To all whom it may concern:

Be it known that I, FREDERICK G. JORDAN, a citizen of the United States, and a resident of Cement, in the county of Pend Oreille and State of Washington, have made certain new and useful Improvements in Reinforcing Elements for Cement and Concrete Work, of which the following is a specification.

10 My present invention relates generally to reinforcing elements for concrete and cement work, and particularly to a reinforcement for walls and structures of the same general character, capable of effective efficient fabrication without the use of bolts and other connections, and without requiring particular tools or especial skill in connection therewith, my object being the provision of a reinforcing element which will admit of ready, 15 efficient fabrication, and at the same time provide interstices therethrough for the cement or concrete whereby to form a strong union and an effective bond.

A further object of my invention is the 20 provision of a reinforcing element in the nature of a web having ribs to strengthen the same, and having its said ribs provided with means to permit of connection of adjacent layers, as well as adjacent reinforcing elements, either inlapping or non-lapping relation, and extending either horizontally, vertically, or angularly, as desired, the said means of attaching adjacent elements being capable of utilization for the 25 support of other and separate parts, all as hereinafter more fully described and set forth.

In the accompanying drawing illustrating my present invention:—

30 Figure 1 is an elevation illustrating several of my improved reinforcing elements in connected relation;

Fig. 2 is an edge view of certain of the members in connected relation;

35 Fig. 3 is an elevation of a portion of a single element;

Fig. 4 is a similar view showing the support of an external part;

Fig. 5 is a sectional view taken substantially on line 5—5 of Fig. 4, and,

Fig. 6 is an edge view of the element shown in Fig. 3.

Referring now to these figures, my invention contemplates the provision of a rectangular reinforcing element having along its opposite sides, ribs 10 and 11, as most

clearly seen by a comparison of Figs. 3 and 6, and having along its central portion a longitudinal rib 12. These ribs 10, 11 and 12 are connected by webs including transverse strips 13 at spaced points in the length of the reinforcing element, and angular arms 14, which join the corners of the spaces thus bound by the longitudinal and transverse ribs, the strips or ribs 13 and 14 60 extending transversely and angularly, leaving between them interstices through which the plastic material is free to pass in order that a rigid union and a uniformly effective bond may be had at all times. 65

The ribs 10 and 11 extending longitudinally along each of the elements, are preferably flanged, so that the sides of each element are not only reinforced, but provision is made for the engagement of adjacent elements along their longitudinal edges. 70

These flanges may be of a reverting or bent back nature, as indicated at 15, in Figs. 5 and 6, the flanged side ribs being slightly offset with respect to the plane of 80 the major portion of the element and the reverting flanges 15 being turned in opposite directions, or the flanges may be turned laterally and be either double on each end, as seen at 16 at one side of Fig. 2, or one 85 flange of each element may be single, as seen at 17, at the left hand side of Fig. 2.

In either case it is obvious that the flanges 15, 16 and 17 provide for the relative engagement of the longitudinal edges of adjacent elements, and to further secure the elements in such engagement, each of the elements may have laterally projecting webs 18 at spaced points therealong, and adjacent the opposite side edges, out of which 90 tongues 19 are struck up so that they may be bent around the engaged edges, or as clearly seen in Fig. 5.

The center ribs 12 are also provided with integral struck up tongues 20 at spaced points in the length thereof, which may be utilized to hold and support a pipe or pipes 21, as seen in Fig. 4, or to engage the central web of an adjacent reinforcing element where the elements are doubled, one extending vertically and the other horizontally. 100

It will be noted that the tongues 20 extend lengthwise of the central ribs 12, while the tongues 19 project transversely with respect to the side ribs 10 and 11, or in other 110 words, at right angles to tongues 20.

In order to strengthen the central ribs

12, they may be crimped to provide either a parallel fold, as seen in Fig. 6, or single or double lateral folds, the last mentioned structure of which is seen in Fig. 2.

5 The various elements when fabricated may have their ends lapped, or elements may be disposed horizontally to lap the adjacent ends of vertically disposed elements, and the horizontally disposed elements, one of which is seen in Fig. 1, may in this case have their central tongues 20 utilized and bent around the connected side ribs of adjacent vertically disposed elements, as may be clearly seen by reference 10 to this figure.

It is thus obvious that my invention provides a reinforcing element for cement and concrete construction which will have a wide application to buildings, ships and 20 other concrete and cement structures, which is susceptible of ready, inexpensive manufacture, and which is capable of effective and efficient use for its intended purposes.

I claim:-

25 1. A reinforcing element for cement and concrete work having spaced parallel ribs at the center and side edges thereof, and having ribs connecting the central and side ribs and forming connecting webs, the said

central and side ribs having integral struck 30 up portions forming connecting tongues, of which the central tongues are disposed longitudinally and the side tongues are disposed transversely, of the element for the purpose described.

2. A reinforcing element for cement and concrete work having spaced parallel ribs at the center and side edges thereof, and having ribs connecting the central and side ribs and forming connecting webs, said central ribs having longitudinally extending 40 and integral tongues struck up therefrom, and said side ribs having transverse integral tongues struck up therefrom for the purpose described.

3. A reinforcing element for cement and concrete work having spaced parallel ribs at the center and side edges thereof, and having ribs connecting the central and side ribs and forming connecting webs, said central and side ribs having integral struck up 50 tongues arranged longitudinally along the central ribs and transversely adjacent to the side ribs, and said side ribs having flanges along the edges thereof for the purpose described.

FREDERICK G. JORDAN.
